A CORPORATION OF CALIFORNIA

ELEVATOR DOOR OPERATOR

Application filed August 16, 1930. Serial No. 475,686.

Our invention relates to operators for closures and has particular reference to operators for opening and closing elevator doors.

Elevator hoistways are provided with entrance openings at each of the floors served by the elevator car and each of these openings is closed by means of a suitable closure or door. These doors are relatively heavy, particularly since it is desirable that they shall be made of fire-proof materials, which renders it difficult to open and close the same.

Also, the traffic requirement in ordinary elevator installations is such that it is desirable to have these doors opened and closed by machinery rather than to depend upon the operator on the elevator car opening and closing them manually.

Various devices for opening and closing elevator hoistway doors have been devised, one popular type comprising a door operating engine to be carried upon the elevator car to engage and open any of the hoistway doors adjacent which the car may be stopped. These prior door operators of this character have the disadvantage, however, that the door operating engine and its mechanism must be of relatively heavy construction since the power for operating the door is to be transmitted from the car to the doors at the entrance openings in the hoistway and in addition these prior types of door operators have always been constructed so that the force exerted in opening the door has been from the car to the hoistway doors. Such constructions are undesirable, first, because of the excessive rigidity of the construction required of the parts which must be employed, and second, because the thrust from the car must be transmitted to the hoistway walls through the guiding devices for the elevator car, that is, the force exerted must react through the guide and if the clearance between shoes and rails is not kept small the car may be moved when doors are operated.

It is, therefore, an object of our invention to provide a device for opening and closing elevator doors in which a single engine carried upon the car may be caused to operate any of the hoistway doors without exerting

a reactive force upon the elevator car structure.

Another object of our invention is to provide an operator for elevator hoistway doors in which a power device may be carried upon the elevator car to operate any one of a plurality of elevator doors by exerting a force on the door and transmitting the reactive force to the elevator hoistway enclosure.

Another object of our invention is to provide an operator for elevator closures in which a single operating engine carried upon the elevator car may be caused to operate any of the doors of the hoistway and may also be adapted to operate the car door or gate carried upon the car.

Another object of our invention is to provide a device for operating elevator hoistway doors in which the doors will be positively opened by means of a force transmitted from the car with a reactive force transmitted to the hoistway walls and in which the doors may be manually opened independent of the position of the door operator.

Another object of our invention is to provide an elevator door operator of the character described in the preceding paragraph in which the reactive force is utilized to operate a lock for the elevator doors.

Another object of our invention is to provide an elevator door operator in which an engine carried on the elevator car may be caused to engage and operate the doors at any of the landings of the hoistway adjacent which the car may be positioned and in which the operation of the door engine to door-closing position will disengage the operator from the door to permit the car to pass the doors without engagement therewith.

Another object of our invention is to provide an operator for elevator doors in which the power for operating the doors is transmitted from the elevator car with the reactive effect transmitted to the wall of the hoistway without exerting a force upon the elevator car, thus permitting a less rigid construction of the apparatus to be employed upon the car.

Our invention will be described with ref-

erence to the accompanying drawings, wherein

Figure 1 is a side elevational view of a door construction in accordance with our invention.

Figure 2 is a side elevational view of the mechanism at each of the hoistway doors to be engaged by the door operator, illustrated in Figure 1.

Figure 3 is a detail view, shown partly in section, of the door operating engine illustrating the mounting thereof on the elevator car.

Figure 4 represents a diagrammatic view illustrating a modified form of our door operator.

Figure 5 is a diagrammatic view of the adaptation of our door operator to a side opening door.

Referring to the drawings, we have illustrated in Figure 1 a fragmentary portion of an elevator car 1 having provided thereon a pair of door sections 2 and 3 which together constitute a closure for the entrance opening to the elevator car 1, the particular style of closure being represented as what is known as "a center opening car door". Around the front portion of the elevator car is a framework comprising upright members 4 and 5 and a cross bar 6 connecting the upper ends of the same, these members being made of any suitable structural steel and being ordinarily provided upon elevator cars for the purpose of constituting a supporting structure for the elevator car door.

Mounted upon a frame 8 superimposed upon the cross member 6, we have illustrated a pair of cam shoes 9 and 10.

The cam shoe 9 is secured, as by a plate 11, extending inwardly therefrom to one arm of a bell crank 12 pivoted at 13 to the cross bar 14 constituting a part of the frame 8. A second bell crank 15 pivoted at 16 and secured to a second plate 17 attached to the cam shoe 9, supports the lower part of the cam shoe 9 and the interconnection of a link 18 between the inwardly extending arms of the bell cranks 12 and 15 insures the vertical alignment of the cam shoe 9 in any of its positions whether retracted or extended.

The cam shoe 9 is spaced forwardly of the elevator car 1 to such position as will permit it, when extended, to engage a cam roller 19, one of which is secured to each of the doors to be operated by our door operator.

The inwardly extending end of the cam shoe plate 11 is connected as by means of a clevis 20 and a rod or bar 21 to a crank pin 22 secured to a rotatable cam 23. The rotatable cam 23 is fixedly mounted upon a shaft 24 which is to be driven by the door operating engine.

Abutting the face of the rotatable cam 23, we have illustrated a roller 25 which is secured to a downwardly extending link 26

pivoted as at 27 to the cross bar 14, and connected as at 28 to a rod or bar 29 which extends in a direction opposite to that of the bar 21 to connect, as by means of a clevis 30, to a plate 31 attached to the cam shoe 10 on the opposite side of the elevator car 1.

The cam shoe 10 is supported in a manner similar to that described for the cam shoe 9, being attached to a triangular plate 32 which is pivoted at 33 to the right-hand upright 34 constituting a part of the frame 8. The lower end of the cam shoe 10 is secured as by means of a plate 35 to a second triangular plate 36 which is also pivoted as at 37 to the upright 34. A link 38 interconnects the inwardly extending portions of the triangular plates 32 and 36 to insure the vertical position of the cam shoe 10 whether extended or retracted.

The cam shoe 10, like the cam shoe 9, is so located forwardly of the elevator car 1 as to be in a position to engage a cam roller 39, one of which is secured to the hoistway wall adjacent each of the door openings to be operated by our operator.

Referring, particularly, to Fig. 3, we have there illustrated the door operating engine which comprises a motor 40 mounted upon a suitable supporting plate 41 connected in any suitable manner to a reduction gear 42, preferably of the worm type. The gearing 42 is connected to rotate a shaft 43 which extends forwardly to connect, as by means of a shaft 44, to the shaft 24 which supports the rotatable cam 23.

With the construction thus far described, the operation of the motor 40 will cause the shafts 43, 44 and 24 to be rotated to thereby rotate the rotatable cam 23 in either a clockwise direction or a counter-clockwise direction, depending upon the direction in which the motor 40 is operated.

For convenience in mounting the door operating engine, the supporting plate 41 may be attached as by means of angle irons 45 and braces 46 to the bifurcated cross head 47 of the elevator car, this cross head 47 being the usual channel beam construction to which the supporting cables 48 for the elevator car are attached.

Referring again to Fig. 1, it will be observed that rotation of the rotatable cam 23 will cause the cam roller 25 to ride from the lowermost face of the cam to the outermost face of the cam to thereby force the rod 29 to the right, thus projecting the cam shoe 10 to the right to engage and move the cam roller 39 also to the right, while at the same time rotation of the rotatable cam 23 will cause the crank pin 22 to move the rod or bar 21 to the left to project the cam shoe 9 to the left to engage the door operating cam roller 19 and move the roller 19 to the left. In order to insure that the movement of the cam shoes 9 and 10 into engagement with their respective rollers to exert a force upon

the door opening devices, will not exert a reactive effect upon the elevator car so as to tend to swing the elevator car, we have illustrated the rotatable cam 23 as being supported upon a link 49 which is pivoted as at 50 to the cross bar 14 of the frame work 8.

Thus if the cam shoe 10 engages its roller 39 and operates the same through its limited amount of movement before the roller 25 passes from the steep face of the cam, further rotation of the cam exerting force of the cam shoe 9 will cause the rotatable cam 23 to shift its position somewhat to the left, which shifting is permissible in view of the sling suspension 49 with which the cam 23 is hung. It will be noted that the relatively steep face of the cam is provided to rapidly take up the clearance space normally allowed between cam shoe 9 and its roller 39.

Referring again particularly to Fig. 3, the link 49 is illustrated as being connected to a shaft 50 which extends through the structural steel members 14 which constitute the cross bar of the frame work, while a second link 51 is also secured to the shaft 50 and to the shaft 24 to constitute a support which will prevent a twisting movement of the shaft 24 under the stress of operating the doors. However, since it is desirable that the cam 23 shall shift its position somewhat with reference to the axis of the main drive shaft 43, it is necessary that the shafting 43, 44 and 24 shall have interposed therein suitable universal joints or couplings which we have illustrated as being located at 52 and 53.

The operation of our device is apparent from a consideration of Fig. 2, in which we have illustrated one of the closures for the hatchway as comprising a pair of door members 54 and 55 suspended as by suitable hangers 56 and 57, respectively, upon a hanger track 58 so that these doors may slide to the left and right, respectively, to constitute what is known as a center opening hatchway door construction. The hanging track 58 is secured to frame work uprights 59 and 60 secured to the walls of the hoistway.

While the doors 54 and 55 may be opened manually, we have illustrated a system of levers and links which may be utilized to automatically open and close the doors as comprising a door opening bar 61 pivotally and slidably connected to the door 54 as by means of a slide 62 which engages a rod 63 secured in any suitable manner as by angle irons 64 to the outer edge of the door 54.

A similar door operating bar 65 is secured to the outer edge of the right hand door 55 in a similar manner.

The door operating bar 61 is pivotally connected as at 66 to a stationary cross bar 67 which connects the upper ends of the uprights 59 and 60 so that movement of the bar 61 around its pivot in a clockwise direc-

tion, that is a movement of the bar 61 to the left, will cause the door 54 to slide on its track to the left.

The bar 65 in like manner is connected as by means of a pivotal connection 68 to a second cross bar 69 which is secured to the uprights 59 and 60 at a position somewhat below the cross bar 67 so that movement of the bar 65 is in a counter-clockwise direction, that is, a movement of this bar to the right, will cause the door 55 to open. Since it is desirable that the door members 54 and 55 shall open simultaneously, the door operating bars 61 and 65 may be interconnected by means of a rod or bar 70 which pivotally connects, as at 71 and 72, with the bars 61 and 65, respectively.

It will be observed that the connecting bar or link 70 connects with the door operating bar 61 at a point somewhat below the pivot point of the bar 61, while the opposite end of the connecting bar or link 70 is connected to the bar 65 at a point above its pivot 68. Thus movement of the bar 61 to the left will exert a force through the connecting bar 70 to cause the bar 65 to move to the right. By suitably selecting the distances between the pivots 66 and 71 and between the pivots 68 and 72, the doors may be caused to be moved to their open positions and to their closed positions in exact synchronism with each other.

In order to insure that the doors 54 and 55 will meet in the center of the door opening when closed, the length of the connecting rod 70 may be made adjustable as by means of a screw and lock-nut connection 73 adjacent one or both of the connecting clevises 71 and 72.

We have illustrated means for applying power to open the doors 54 and 55 as constituting the cam roller 19, previously described as being in a position to be engaged by the cam shoe 9, as being rotatably supported upon a cam lever 74, pivotally secured as at 75 to the cross bar 69 rigidly secured to the hoistway walls as by connection to the uprights 59 and 60. At a point between the pivot 75 and the roller 19 a link 76 is connected to the lever 74, the opposite end of the link 76 pivotally connecting, as at 77, with the door operating bar 61. With this construction, it will be apparent that a movement of the cam roller 19 to the left under the influence of the cam shoe 9, will rotate the cam lever 74 to pull the bar 61 to the left and thus open the door 54, which by its interconnection through the connecting rod 70 will also cause the simultaneous opening of the door 55.

The doors 54 and 55 are normally biased to a closed position by means of a relatively heavy spring 78, which is connected between the bar 61 and a suitable supporting stud 79 which in turn is secured between the cross bars 67 and 69. The spring 78 may be made adjustable, if desired, by connecting the same

to the stud 79 as by means of an adjustable eye-bolt 80 which may be adjustably secured in its adjusted position by means of nuts 81. The doors which are employed in elevator service are relatively heavy and considerable force must be exerted in opening and closing the same, which force must be applied from the door operator. With the employment of a single door engine which is to be carried upon the elevator car, it is necessary that the reactive force set up when the door engine operates to open the door, as in the system illustrated by projecting the cam shoe 9 to the left to engage and operate the cam roller 19, shall be absorbed.

In previous types of door operators this reactive force has been absorbed by the elevator car, the force being transmitted through the elevator car to its guide rails and thence to the rigid construction of the hoistway walls.

However, in a door operator constructed in accordance with our invention, the reactive force is not transmitted to the elevator car, but is instead transmitted to the opposite hoistway wall so that a rigid purchase may be obtained on the hoistway walls against which the thrust of the door operating cam shoe may be taken.

We have illustrated a system for absorbing this reactive force or applying the same to the side of the hoistway wall opposite to that upon which the door operating cam roller 19 is mounted, by allowing the cam shoe 10 on the right hand side of the elevator car to engage its roller 39 so that the force exerted is transmitted through a lever 82 to the upright 59 to which the lever 82 is secured as by means of a pivotal connection 83.

While it will be understood that it is unnecessary that the cam shoe 10 shall engage a roller or a lever and may in fact impinge directly upon the upright 59, we have utilized the roller and lever construction so that the reactive force may be employed for the purpose of unlocking the doors, operating door and interlocking switches, or other devices which may be required to be actuated at the instant of initiating the opening operation of the door. For this purpose, we have illustrated the lever 82 as having a limited movement about its pivot 83 between a pair of stops 84 and 85, which engage opposite sides of the lever 82 but may be adjusted to limit the movement of the lever 82 to the right and left, respectively. The extending arm 86 of the lever 82 is illustrated as being connected as by means of a link 87 to a bell crank 88 which is pivotally secured in any suitable manner, as illustrated at 89, to the cross bar 69 so that the depending arm of the bell crank 88 is in a position to engage a locking plate 90 secured to the hanger 57 for the door 55.

In the normal position of the lever 82, to which it is biased by means of a spring 91, the bell crank lever 88 will be in such position

as to engage the plate 90 and prevent movement of the door 55 to the right, that is, will prevent movement of the door 55 to an open position while the engagement of the roller 39 by the cam shoe 10, will rotate the lever 82 through a sufficient distance to rock the bell crank 88 to a position where it will disengage the locking plate 90 to allow the doors to be operated. An interlock switch 123 may be connected to the bell crank 88 to open the elevator motor circuit whenever the doors are unlocked.

With the construction thus far described, the movement of the elevator car 1 to the floor landing with which hoistway doors 54 and 55 are associated, will position the cam shoes 9 and 10, carried by the car, in the positions illustrated in Fig. 2.

Operation of the motor 40 to rotate the rotatable cam 23 in a clockwise direction, will cause extension of the cam shoe 10 by virtue of the riding of the cam rollers 25 from the lower face of the cam to its outermost face. This operation will project the cam shoe 10 into engagement with the cam roller 39 associated therewith and will cause a rocking of the lever 82 to unlock the door. At this time the lever 82 will abut the stop 84 so that no further movement of the cam shoe 10 to the right is permitted. In other words, the bar 29 which operates the cam shoe 10 is now abutting a fixed support secured rigidly to the hoistway walls.

The cam 23 may be so shaped and crank pin 22 so located that there is no horizontal movement of lever 31 until cam roller 25 rides upon the high part of cam 23 and the door is unlocked.

Simultaneously with the projection of the cam shoe 10, the rotation of the rotatable cam 23 will move its crank arm 22 in a clockwise direction to move the rod 21 to the left to thereby project the cam shoe 9 to a position to engage and move its associated cam roller 19 to the left, thus applying the necessary power to operate the door opening bars 61 and 65 and open the doors. It will be observed that the crank arm 22 on the cam 23 will move through an arc comprising a little more than 180° , starting from a point just beyond the dead center and complete its movement at approximately dead center, thus insuring a harmonic motion which causes the doors to be started, slowly accelerated through the major part of their motion, and decelerated through the latter part of their motion to open position, this being the most desirable operation of elevator doors, and rendering unnecessary the employment of retarding devices such as dashpots to stop the doors in either their open or closed position. By adjusting the relative positions of the crank arm 22 with respect to the cam shoe 9 so that a slight movement is required before the crank arm starts its movement to the left,

permits insurance that the cam roller 25 will be actuated to cause an unlocking of the doors and the abutting of the cam shoe 10 against a rigid support before any force is exerted 5 tending to open the doors.

When it is desired to close the doors, the motor 40 may be reversed to rotate the rotatable cam 23 in a counter-clockwise direction to thereby retract the cam shoe 9, where- 10 upon the spring 78 will move the door operating levers 61 and 65 to the right and left respectively to close the doors. By suitable selection and adjustment of the force exerted by the spring 78, the cam roller 19 may be 15 caused to continuously engage the cam shoe 9 during the entire closing movement, thus eliminating the necessity for providing dash-pots or other retarding devices for stopping the doors when they arrive in their closed po- 20 sition since the continuous engagement of the roller 19 with the cam 9 insures that the force exerted by the doors in moving to their closed position shall be absorbed by the har- 25 monic crank motion by the crank 22. When the doors have arrived in their closed posi- 30 tion and the crank arm 22 moves to its dead center position on the right hand side of the shaft 24, the cam roller 25 will enter upon the lower face of the cam 23 to withdraw the 35 cam shoe 10, thus allowing the locking bell crank 88 to lock the doors, and when the rotatable cam is in this position the cam shoes 9 and 10 are retracted to their normal posi- 40 tions so as to provide ample clearance be- 45 tween the shoes 9 and 10 and their respective rollers 19 and 39 so that the car may move away from the floor and may pass other floors without engaging the cam rollers 19 and 39 50 associated therewith.

It will be observed that the function of the spring 78 is primarily to insure closing of the door and to insure that the door will be held closed except at such times as the cam shoes 9 and 10 are operated to open the same. In 55 addition, however, the spring performs two important functions; first, during the opening movement of the door the spring is building up a force tending to close the door and assists therefore in retarding the door as it approaches its full open position, the spring tension at that time being at its greatest 60 second, during the closing movement of the door the spring acts to accelerate the door toward its closing position, at which time the spring tension is at its greatest and hence, 65 its accelerating effect will be greatest. However, after the door has been accelerated the momentum of the door is almost sufficient to carry the doors through to their closed position and the spring tension required during 70 the latter part of the movement need be but small. Hence, the additional advantage is achieved that a comparatively light spring may be employed for this purpose so that 75 should the doors strike persons who may be

passing into or out of the elevator during the closing movement of the doors will receive but a slight shock and will not be injured, as would be the case if a heavy spring force were required for the entire closing movement. 70

The retraction of the cam shoes 10 and 11 as hereinbefore stated, provides the necessary clearance to allow the elevator car to pass hoistway doors and floors at which the car is not to stop, without contacting with the rollers 19 and 39 at those doors. In view of the fact that the rotatable cam 23 is mounted to float with reference to the car it may occur that the cam 23 would assume such position that one or the other of the cam shoes might be in a position to engage the rollers 19 or 30 at a time when it was not desired, and for this reason we have provided a centering device for insuring the return of the floating cam 23 to its central position, 75 thus insuring clearance of both of the cam shoes 9 and 10. This centering device is illustrated in Figure 1 as comprising a pair of pivoted levers 110 and 111 pivoted at their lowermost ends upon the same member to 80 which the cam supporting link 51 is pivoted, the upper ends of the two pivoted levers 110 and 111 being connected together as by means of a rod 112 passing through both of the levers and having springs 113 and 114 normally 85 tending to keep the levers close to each other and in engagement with a stationary stop 115. The link 51 may be provided with an up- 90 standing projection 116 which enters between the levers 110 and 111, so that dis- 95 placement of the cam 23 and the link 51 to either the right or left will engage and operate one of the levers 110 or 111 and compress the spring associated therewith.

Upon retraction of the cam shoes 9 and 10, 100 thus relieving the cam 23 to its displacing force, the compressed spring 113 or 114 will press the associated lever to restore the cam to its central position.

While the force of gravity should be suffi- 110 cient to cause retraction of the cam shoe 10 when the rotatable cam 23 is in its normal retracting position, we prefer to make the retraction of the cam shoe 10 more positive by providing a tensioning device biasing the cam roller 25 toward the cam 23. This de- 115 vice is illustrated in Figure 1 as comprising an eye-bolt 117 connected as at 118 to the link 51, and passing through the link 26, having a spring 119 thereon under compres- 120 sion, constantly exerting a force tending to move the link 26 toward the cam 23.

It will be further observed that by reason of the floating mounting of the cam 23 the lateral position of the car with respect to the hoistway doors at the time the car arrives at the landing is not material since if the car should by any reason have a sideways motion, this motion is not transmitted to the door operating cam shoes 9 and 10 and so does not 125 130

affect the operation of the doors in any way.

It will be readily apparent that the selection of the distance between the shaft 24 and the point on the face of the cam 23 at which the crank pin 22 is located may be suitably selected to determine the length of throw of the door operating cam shoe 9, while the selection of the configuration of the face of the cam 23 may also be suitably selected to give any desired speed of operation to the cam shoe 10 and likewise any desired amount of throw for this cam shoe. Thus the pre-selection of the location of the crank pin and the configuration of the face of the cam once determine for the particular door installation to which it is to be applied, requires thereafter little or no adjustment.

Moreover, since the speed of operation of the doors is determined only by the speed of rotation of the cam 23 the selection of a motor of the desired speed or the selection of gearing to produce the desired speed allows considerable latitude for providing a door operating speed of any desired value. Moreover, by utilizing a motor having a constant speed characteristic the door operating speed which has been selected will be maintained substantially constant, regardless of the variation in friction of several doors which are to be operated by the operator.

The utilization of the crank arm motion for operating the cam shoe 10 allows the cam 23 to overrun by a considerable distance the full amount required to open the doors, without permitting the doors to start reclosing, while at the same time the configuration of the cam face allows considerable latitude for overrunning of the cam without altering the position of the cam shoe 10. Thus, the motor 40 may be provided with a suitable limit switch to insure its stoppage after the doors have been completely opened or completely closed, which switch does not require extremely accurate adjustment for accurate results. Such limit switch is illustrated in Figure 3 as comprising a switch 120 mounted upon the gear case 42 in a position to be engaged by a limit switch pin 121 secured to gear 122 mounted upon the shaft 43.

While we have illustrated but a single installation of doors 54 and 55 and their associated operating mechanism, it will be understood that the doors and operating apparatus will be duplicated for each of the floors which are served by the car.

If the elevator car is equipped with a car door or a closure carried thereby for closing the entrance opening to the cab, such car gate may also be operated by the same door operating engine.

Referring to Figure 1, we have illustrated the car door as comprising the sections 2 and 3 necessary to constitute a center opening door. The sections of the car door are connected to suitable door opening levers

92 and 93 in the usual manner with which door operating levers are so connected but are not illustrated in the drawings. Lever 92 is illustrated as being pivoted as at 94 to a plate 95 which extends upwardly from the cross bar 6 connecting the operating frame members 4 and 5, while lever 93 is also pivoted as at 96 to the cross bar 6. In order that the gate sections 2 and 3 will move to their open and closed positions synchronously, we have illustrated a cross connecting link 98 similar to the link 70 described with reference to the hoistway doors, which connects to the lever 92 at its pivot and to the lever 93 above its pivot, the distances between the two connections to the pivots being suitably selected to achieve the synchronous operation of the two doors.

For the purpose of applying power to the levers 92 and 93 to open the doors, we have illustrated the cross connecting link 98 as being pivotally connected at a point 99 to a lever 100 which extends upwardly into engaging relation with a second cam 101 which is to be driven by the motor 40.

The upper end of the lever 100 is provided with a cam engaging roller 102 to reduce the friction between the cam 101 and the lever 100. While the lever 100 may be mounted in any suitable manner, we have illustrated the same as being pivoted at its center 103 to a framework 104 which extends between the upper cross member 8 and the lower cross member 6, constituting the supporting frame for the door operating structure.

We have also illustrated a means for normally maintaining the car gate in closed position as comprising a spring 105 connected as at 106 to the lever 92 at a point below its pivot 94, the other end of the spring 105 being connected as at 107 to frame 104. By securing the spring 105, as by means of an eye-bolt 108, the tension upon this spring may be adjusted to insure the proper amount of force necessary to maintain the doors in closed position and to govern the closing action of these gates.

The function of the spring 105 is similar in all respects to the function of the spring 78 described with reference to the hoistway door operating structure, that is, spring 105 performs the function of biasing the car doors passing the car gate to closed position and acts during the opening movement of the car gate to decelerate the gate when it arrives at the open position and in like manner acts to accelerate the gates when they are started upon their closing movement.

If desired the spring 105 may be made of comparatively light construction and an auxiliary spring 124 may be provided for assisting the spring 105 to perform its decelerating and accelerating functions. The spring 124 is illustrated as being mounted upon an eye-bolt 125, one end of which is secured to

the gate operating bar 92, the other end of which passes loosely through an abutment 126 secured to the structural cross member 104. By providing a shoulder 127 upon the eye-bolt 125 at a distance away from the abutment 126 greater than the length of the spring 124, it will be apparent that upon the initial opening movement of the doors the spring 124 will have no effect, while as the doors approach their full open position the shoulder 127 on the bolt 125 will engage and compress the spring 124, thus adding the force of this spring to that of the spring 105 to assist in the deceleration operation. A similar auxiliary spring construction may be provided for the hoistway doors to assist the spring 78 to perform its accelerating and decelerating functions if desired.

Referring, particularly, to Figure 3, it will be observed that the car door operating cam 101 is mounted upon a shaft 128 which is secured to a gear 129. The gear 129 is in turn engaged by the gear 122 secured to the shaft 43 which is used to drive the hoistway door operating cam 23.

With this construction, it will be apparent that the motor 40 will simultaneously rotate the hoistway door operating cam 23 and the door operating cam 101 and by selecting the shape of the cam 101 and the ratio of gears 129 and 122, the hoistway doors to the car gate may be caused to move to their open and closed positions in exact synchronism with each other.

In Figure 4 we have illustrated a modified form of our door operating device in which the reactive effect of opening the doors is self-absorbed by the doors without transmitting this reaction to the elevator car structure.

Referring particularly to Figure 4, we have illustrated a rotatable member 23' secured to a shaft 24' and corresponding in substantially all respects with the rotatable cam 23 illustrated with the form of our device described in Figure 1. At diametrically opposite points on the rotatable member 23' we have illustrated crank pins 22' and 22'' to which are respectively secured links 21' and 21''. The link 21' is connected to a cam shoe

9' similar in all respects to the cam shoe described with reference to Figure 1, while a cam shoe 9'' is similarly connected to the link 21''. It will be apparent that the structure just described is to be carried by the car and is to be operated by a suitable motor in the manner described with reference to the modification we mention shown in Figure 1. It will also be understood that the rotatable member 23' is floatingly mounted upon the elevator car as described with reference to Figure 1.

In Figure 4 we have illustrated a center opening door structure comprising door panels 54' and 55', each of which is connected as by means of door opening bars 61' and 65'

with suitable pivots 66' and 68', respectively. The door operating bar 61' is illustrated as being connected to a cam lever 74'' located at such position as to be engaged by the cam shoe 9'' when that shoe is extended, while the door operating bar 65' is in like manner secured to a cam lever 74' engageable and operable by cam shoe 9'. The operation of this modification of our device is as follows:

The elevator car upon arriving at a position adjacent the floor represented by the doors 54' and 55' will have the door operating motor energized to rotate the rotatable member 23' to thereby expand the cam shoe 9' and 9'', each of which will engage and move its associated cam lever 74' and 74'' to open the associated door panel. The door panels may be interconnected as by means of linkage 70' to insure the synchronous opening of the two sections of the door. In the modification thus described the reactive effect of opening either panel of the door is taken up by the force required to open the other door panel.

Referring particularly to Figure 5, we have illustrated the adaptation of the door operating device illustrated in Figures 1 to 3 to a side opening elevator hoistway door. The door illustrated comprises a pair of panels 131 and 132 each mounted for movement by means of suitable hanger members 133. The type of side opening door illustrated is known as the two-spaced door in which the panel 131 is to be moved at twice the speed of the panel 132 so that the two panels arrive in their open position at the same instant. The panel 131 is connected as by means of a door operating bar 134 to a stationary pivot 135 and has connected thereto a cam lever 74'' similar in all respects to cam 74 described with reference to Figure 1 engageable by a cam shoe 9'' similar to the shoe described in Figure 1. The door operating bar 134 is connected to the panel 132 by means of a link 136 which engages the bar 134 at a point intermediate its pivot 135 and its point of attachment to the panel 131.

We have also illustrated in Figure 5 a door locking device similar to that described with reference to Figures 1, 2 and 3 as comprising a door latch 137 mounted upon a bellcrank 138 which in turn is connected by a link 139 to a cam lever 140 which is engageable by a cam shoe 10'' on the operating device to be carried by the car.

The operation of the form of our invention as illustrated in Figure 5 is as follows:

Upon the arrival of the car at the floor represented by the door panels 131 and 132, the door operated motor 40 may be started to rotate the cam 23 to thus extend the cam shoe 9'' and 10'' in the manner described with reference to Figures 1, 2 and 3. The engagement of the cam shoe 10'' with the cam lever 140 unlocks the door, while the engagement

and movement of the cam lever 74^a pulls the door operating bar 134 to the left to open the panel 131 and by reason of its connection with the panel 132, the panel 132 is also moved. 5 By suitably selecting the lengths of the respective portions of the door operating lever 134 lying between the post 135 and the point of attachment of the link 136, the two panels may be operated at such speeds as to cause 10 them to arrive at their open and closed positions simultaneously.

While we have described the preferred embodiment of our invention, we do not desire to be limited to any of the details shown or 15 described herein, except as defined in the appended claims.

We claim:

1. In combination with a door for an elevator hoistway, an elevator car, and a door operator carried by said car including means for engaging said door to move the same, means for engaging said hoistway and power means for moving said door engaging means and said hoistway engaging means relative 20 to each other.

2. In combination with a door for an elevator hoistway, an elevator car, and a door operator carried by said car including cam means for engaging said door to move the same, cam means for engaging said hoistway and power means for moving said two cam means relative to each other.

3. In combination with a door for an elevator hoistway, an elevator car, a door operator carried by said car including cam means for engaging said door to move the same, cam means for engaging said hoistway, power actuated means for moving said two cam means relative to each other, and means 35 mounting said power actuated means for free movement relative to said car.

4. In combination with a door for an elevator hoistway, an elevator car, and a door operator carried by said car including cam means for engaging said door to move the same, cam means for engaging said hoistway, rotatable means connecting said two cam means for moving said two cam means relative to each other, and means mounting said 40 rotatable means for free movement relative to said car.

5. In combination with a door for an elevator hoistway, an elevator car and a door operator carried by said car including a door engaging member, a hoistway engaging member, and power means connecting said two members for simultaneously moving the same in opposite directions.

6. In combination with a door for an elevator hoistway, an elevator car and a door operator carried by said car including a hoistway engaging member, a door engaging member and a power actuated means connecting said members for moving said hoistway member into engagement with said hatchway

and for moving said door engaging members into engagement with said door, said power actuated means being movable relative to said car whereby the forces exerted in opening said door are applied directly between said hoistway and said door. 70

7. In combination with a door for an elevator hoistway, an elevator car and a door operator carried by said car including a hoistway engaging member, a door engaging member and a power actuated means connecting said members for moving said hoistway member into engagement with said hoistway and for moving said door engaging members into engagement with said door, said power actuated means being movable relative to said car whereby the forces exerted in opening said door are applied directly between said hoistway and said door, means for locking said door, and means interposed between said hoistway engaging means and said hoistway for operating said locking means to release said door upon actuation of said hoistway engaging means. 75

8. In combination with a door for an elevator hoistway, an elevator car and a door operator carried by said car including a hoistway engaging member, a door engaging member and a power actuated means connecting said members for moving said hoistway member into engagement with said hoistway and for moving said door engaging members into engagement with said door, said power actuated means being movable relative to said car whereby the forces exerted in opening said door are applied directly between said hoistway and said door, means for locking said door, and means actuated by said hoistway engaging means when moved into engagement with said hoistway for releasing 85 said locking means. 90

9. In combination with a door for an elevator hoistway, an elevator car and a door operator carried by said car including a door moving cam, a hoistway engaging cam, rotatable means connecting with said door moving cam for applying power to said door, and cam means on said rotatable means for moving said hoistway engaging means into engagement with said hoistway prior to applying 100 power to said door. 110

10. In combination with a door for an elevator hoistway, an elevator car, a door operating engine carried by said car comprising a rotatable member mounted to freely move in one plane with respect to said car, means for rotating said member, a door engaging cam connected to said rotatable member for moving thereby as said rotatable member rotates, and a hoistway engaging member operable by said rotatable member in a direction opposite to that of the door engaging cam. 120

11. In a device for operating an elevator hoistway door having a system of levers 130

therefor operable by a thrust thereon in a given plane, a door operating engine carried by said car comprising power driven means for engaging said door lever system to produce a thrust in the said plane, and a hoistway engaging means operable to engage said door operating engine with the hoistway wall substantially in the same plane to transmit the reaction of the thrust to the hatchway wall.

12. In a device for operating an elevator hoistway door having a system of levers therefor operable by a thrust thereon in a given plane, a door operating engine carried by said car comprising a rotatable cam member, power means for rotating said cam member, a crank on said cam member connecting with a door engaging cam shoe, a hoistway engaging cam shoe in camming engagement with said rotatable cam to engage said rotatable member with the hoistway to absorb the reactive force exerted thereby in moving said door cam shoe to operate said door.

13. An elevator door operator to be carried by an elevator car comprising a rotatable member, power means for rotating said member, a door engaging means connected with said member for reciprocatory movement upon rotation of said member to engage and move the door, a hatchway engaging means also operable upon rotation of said member to apply the reactive forces exerted by the door engaging means to the hoistway structure, and means mounting said rotatable member for lateral movement under the influence of said door engaging means and said hoistway engaging means.

14. A door operating device to be carried by an elevator car for simultaneously operating the hoistway doors and elevator car gate of an elevator system including a power device, a rotatable member driven thereby, a hoistway door engaging means and a hoistway engaging means operable by said rotatable member to engagement with the door and the hoistway respectively, means mounting said rotatable member for movement relative to the car in the direction of movement of said engaging means, a second rotatable member also driven by said power means for engaging and operating the car gate when said second rotatable member is rotated.

15. An elevator door operator to be carried by an elevator car comprising a power device, a rotatable cam driven thereby, a door engaging means connected to said cam for crank motion thereby, a hoistway engaging means arranged for camming movement by said cam, said two means being arranged on said cam in such manner that upon rotation of said cam the cam motion precedes the movement of said door engaging means.

16. In a device for operating an elevator hoistway door having a system of levers

therefor operable by a thrust thereon in a given plane, means normally biasing said lever system to move said door to closed position, a door operating engine carried by said car comprising power driven means for engaging said door lever system to produce a thrust in the said plane, a hoistway engaging means operable to engage said door operating engine with the hoistway structure, a rotatable device driven by said engine for moving said door engaging means into engaging position and for retracting the same, said biasing means on said door maintaining the door engaged with said door engine during substantially all of the retracting movement.

17. In an elevator door operator a pair of door engaging cam shoes, a rotatable member connected to said cam shoes and operable upon rotation thereof to extend and retract said cam shoes, said rotatable member and said cam shoes being located in substantially the same vertical plane, and means mounting said cam shoes and said rotatable member on the elevator car for lateral movement relative to the car in the said vertical plane.

18. In combination with an elevator door having a pair of door operating levers movable in opposite directions to move the door, an elevator door operator comprising a pair of door engaging cam shoes, a rotatable member connected to said cam shoes and operable upon rotation thereof to extend and retract said cam shoes, said rotatable member and said cam shoes being located in substantially the same vertical plane, and means mounting said cam shoes and said rotatable member on the elevator car for lateral movement relative to the car in the said vertical plane, said cam shoes being engageable respectively with opposite door levers whereby the reaction of force applied to one lever is absorbed by the other lever.

Signed at Los Angeles, California, this 16th day of July, 1930.
